US0D1028991S

(12) **United States Design Patent** (10) **Patent No.:** **US D1,028,991 S**
(45) **Date of Patent:** **** May 28, 2024**

(54) **ELECTRONIC DEVICE COVER**

(71) Applicant: **Amazon Technologies, Inc.**, Seattle, WA (US)

(72) Inventors: **Muye Guang**, Sunnyvale, CA (US); **Paul Van Gasse**, Sunnyvale, CA (US); **Tim Wall**, Mill Valley, CA (US)

(73) Assignee: **AMAZON TECHNOLOGIES, INC.**, Seattle, WA (US)

(**) Term: **15 Years**

(21) Appl. No.: **29/867,983**

(22) Filed: **Nov. 15, 2022**

Related U.S. Application Data

(62) Division of application No. 29/683,161, filed on Mar. 11, 2019, now Pat. No. Des. 975,097.

(57) **CLAIM**

The ornamental design for an electronic device cover, as shown and described.

DESCRIPTION

FIG. 1 is a front perspective view of the electronic device cover;

FIG. 2 is a back perspective view thereof;

FIG. 3 is a right-side view thereof;

FIG. 4 is a left-side view thereof;

FIG. 5 is a top view thereof;

FIG. 6 is a bottom view thereof;

FIG. 7 is a front view thereof;

FIG. 8 is a back view thereof;

FIG. 9 is a front perspective view of the electronic device cover with a stand of the electronic device cover extended;

FIG. 10 is a back perspective view thereof;

FIG. 11 is a right-side view thereof;

FIG. 12 is a left-side view thereof;

FIG. 13 is a top view thereof;

FIG. 14 is a bottom view thereof;

FIG. 15 is a front view thereof; and,

FIG. 16 is a back view thereof.

The dashed broken lines depict portions of the electronic device cover that form no part of the claimed design.

1 Claim, 16 Drawing Sheets
